UNITED STATES PATENT OFFICE.

BION E. MARTIN AND D. EVERETT MARTIN, OF SYCAMORE, OHIO.

HALTER-TRIMMING.

SPECIFICATION forming part of Letters Patent No. 366,416, dated July 12, 1887.

Application filed March 11, 1887. Serial No. 230,539. (No model.)

To all whom it may concern:

Be it known that we, BION E. MARTIN and D. EVERETT MARTIN, of Sycamore, in the county of Wyandot and State of Ohio, have 5 invented a new and Improved Web-Adjuster for Halters, &c., of which the following is a full, clear, and exact description.

Our invention consists of a web-holding device designed more especially for use in web 10 halters for holding the web and for adjusting it to increase or diminish the size of the halter.

Reference is to be had to the accompanying drawings, forming a part of this specification, in which similar letters of reference indicate 15 corresponding parts in all the figures.

Figure 1 illustrates a halter having our web holder and adjuster applied thereto. Fig. 2 is an enlarged view of the adjuster, showing the ends of the web and a strap held therein. 20 Fig. 3 is a sectional elevation of the same, taken on the line *y y* of Fig. 2. Fig. 4 is a sectional plan view on the line *xx*, Fig. 2. Fig. 5 shows a modified form of the adjuster free from webs or straps. Fig. 6 shows an adjuster constructed to receive two lower or side webs; and Fig. 7 is a sectional plan view of the same, taken on the line *w w* of Fig. 6.

The web-adjuster A, Figs. 1 and 2, is constructed to hold and to enable the adjustment 30 of the cheek-web *a* and the nose-piece *b* of the halter, and also the chin-strap *c*, which is secured in the side bow, *d*, of the adjuster, the said bow being curved outward for that purpose below the central transverse bar, *e*, as shown clearly in Fig. 2. The bar *e* is joined to and made a part of the main surrounding frame of the adjuster, which is composed of the side pieces, *f f'*, and end pieces, *f'' f'''*. Between the central cross-piece, *e*, and the upper 35 end piece, *f''*, are the transverse cross pieces, *h h'*, while between the central piece, *e*, and the end pieces, *f'''*, are the vertical bars *i i'*. To connect the web *a*, one of its ends is passed under the end piece, *f''*, around the bar *h'*, and 40 back over the bar *h*, between said bar and the web. In this manner the web is self-binding, so that it cannot slip in the adjuster, and by

slipping the web through the adjuster to the position shown in dotted lines in Fig. 3 the end may be easily drawn through to take up the 50 slack, and the web thus easily adjusted.

The web *b* may be attached to and adjusted in the device in like manner by passing the web under the side piece, *f*, around the bar *i'*, and back between the web and the bar *i*, as 55 shown clearly in Fig. 4. The webs *a b* are thus held at right angles to each other, and may be easily taken up and let out to suit the occasion.

In the form of adjuster shown in Fig. 5 the 60 bow *d* in the side piece, *f'*, is omitted, and in Figs. 6 and 7 the vertical bars *i i'* are duplicated in the lower part of the adjuster, so that in place of an ordinary strap, *c*, as in Fig. 1, a web, *b'*, may be attached to the adjuster in 55 line with the web *b*, and said web adjusted and held in the same manner as the webs *a b*, described above.

By constructing the adjuster as described, and by applying it as described, the web may 70 be adjusted to increase or diminish the size of the halter, and by passing the web over and under the cross pieces, as shown in Figs. 3, 4, and 5, so that the outer web compresses the end of the web between it and the bar, any strain 75 upon the web renders it self-binding in the adjuster or holder.

Having thus described our invention, what we claim as new, and desire to secure by Letters Patent, is—

The web holder and adjuster A, composed 80 of the main frame, the central bar, *e*, the two transverse bars *h h'* above the central bar, and the four vertical bars *i i'* below the central bar, in combination with the web passed over 85 and under the bars *h h'* and *i i'*, so that the strain upon the web renders it self-binding in the holder, substantially as described.

BION E. MARTIN.
D. EVERETT MARTIN.
